UNITED STATES PATENT OFFICE

2,454,234

PORTABLE ALARM

Samuel Sundel, Philadelphia, Pa., assignor of one-half to Alexander Sundel and one-half to Christ Bastis, both of New York, N. Y.

Application April 12, 1945, Serial No. 587,875

2 Claims. (Cl. 200—54)

1

The device of the present invention is an improvement on my previous patents, No. 1,099,777, of June 9, 1914, and No. 1,377,939 of May 10, 1921, on Portable burglar alarms. This invention accomplishes all the objects of my prior patents by use of a much simpler mechanism, employing fewer parts and eliminating the necessity of securing or anchoring part of the mechanism.

The invention also contemplates an alarm which is more positive in operation and may be adjusted to conform to variations in door and door frame constructions.

Other objects of the invention will be manifest from the following description of the present preferred form of the invention, taken in connection with the accompanying drawings, wherein:

Figure 1 is a front elevational view of an alarm constructed in accordance with the present invention illustrating its application;

Figure 2 is a top plan view of the same;

Figure 3 is a side elevational view of the adjustable door jamb engaging plate and detent; and

Figure 4 is a fragmentary top plan view of a modified form of the invention showing the free end of the reversible lever in spaced relation to its contact plate.

In order to illustrate the application of the invention, a door jamb or frame 5 is shown, in which a door 6 is mounted in a manner well known in the art.

The device of my invention consists of a self contained portable unit, capable of application to any movable or fixed object. When used as a burglar alarm, the unit is mounted upon the door, operation being effected upon opening the door. The unit embodies a panel 7 which is equipped with a pair of supporting plates 8, each of the plates having an eye adapted for the reception of a screw 9. The screws may be engaged in the door as illustrated in the drawing. The panel carries on its front face, an audible signal, generally designated 10, which, in this instance, is shown to be an electric bell, the clapper 11 of which is operated by electro-magnets 12. The electro-magnets are in circuit, as indicated at 13, with batteries 14 which are detachably mounted in a cylindrical case 15. The bottom of the case is equipped with a removable cap 16 which carries a spring 17 that normally urges the batteries upwardly in the case 15 to engage a contact 18 detachably mounted on the panel.

The bell circuit is closed in the present embodiment of the invention by the opening of the door. The specific means used in the present in-

2

stance for performing this function, includes a reversible inherently resilient lever 19, one end of which is spaced from and pivotally engaged to the panel, being secured from displacement by 5 a wing nut 20 threaded on a supplemental shaft 20', as illustrated to advantage in Figure 2. The opposite end of the lever extends beyond one side of the panel 7 and is bent at right angles as indicated at 21. The right angle extension 21 carries 10 a bifurcated plate 22, the branches of the bifurcation straddling a threaded shank 23 which extends outwardly from the right angled portion 21 of the reversible lever and is engaged with a thumb nut 24. The door jamb engaging end of 15 the plate 22 carries a pivotally mounted spacer 25 which is adapted to engage the door jamb when the device of the present invention is used as a burglar alarm.

Contact strips 26 are mounted on the outer 20 face of the panel 7 at the upper end of the latter, both of the strips being in electrical communication, as illustrated in the drawing, with the contact 18. The lever 19 is adapted to be positioned over either of the strips 26 to close the circuit 25 and sound the alarm. The lever 19 is normally held in spaced relation to its underlying strip, by an adjusting screw 27. The screw is hand operated and may be urged, in an obvious manner, into engagement with the panel 7. By use of the 30 screw 27, adjustment of the reversible lever 19 may be made to retain the lever spaced from its subjacent strip 26.

The device is used as a burglar alarm in the following manner: The screw 27 is adjusted to 35 hold the lever 19 out of contact with the strip 26 and the panel 7 is secured to an open door 6. The pivoted spacer 25 is then manually maintained in its extended position (shown by dotted lines in Figure 3) as the door 6 is moved to its closed 40 position. The spacer 25 then engages the door frame 5 and the lever 19 is held in spaced relationship with the contact 26. The screw 27 is next unscrewed so that it cannot prevent the 45 lever 19 from moving into contact with strip 26 when the door is opened by a prowler. The device is now set.

When the door 6 is opened, the lever 19 springs into contact with the strip 26 and the alarm is sounded. The moment the pivoted spacer 25 50 leaves the door frame 5, the spacer swings downwardly to the position shown in Figure 3. Then, if the unauthorized person opening the door quickly shuts the door upon hearing the alarm, his closing of the door will not shut off the alarm 55 because after the spacer 25 has dropped down,

the lever 19 remains in contact with the strip 26 even though the door is closed. By this construction, the occupant of the room is fully aroused and warned of the attempted entrance. The occupant himself must turn off the alarm by urging screw 27 against the panel 7. He can then instigate an investigation of the premises.

In the event the device is to be used as an ordinary doorbell, the detent 25 is not set. By bifurcating the plate 22, the latter may be adjusted so as to conform to variations in door and door jamb constructions and contours. When the device is to be rendered inoperative, the screw 27 is urged against the panel so as to feed the operating end of the reversible lever outwardly; or if desired, the lever may be swung on its axis so as to place the operative end thereof at a point above the panel. By providing strips 26 at opposite sides of the panel 7, the alarm may be used with a door opening from either side of the door jamb.

Should it be desired to use the present invention as a fire alarm, the panel 7 is secured to a fixed object in a room and a cable 28 engaged with the free end of the lever 19. The cable is drawn taut to pull the lever away from the contact strip 26. The cable may be made of fusible or ignitable material to break when exposed to a flame or when subjected to predetermined temperatures. Any failure of the cable 28 results in sounding the alarm. This includes breakage of the cable such as by contact of a part of the body of an intruder therewith.

While I have herein described a preferred embodiment of this invention, it is to be understood that various changes may be made therein within the scope of the claims hereto appended.

What I claim is:

1. In a portable self-contained alarm of the type including a mounting panel adapted to be secured to a closure, a circuit maker and breaker embodying a pair of relatively spaced contacts fixedly secured to the panel, a resilient contact strip pivoted to the panel and movable about its pivot into a position overlying a selected one of the fixed contacts and extending beyond the edge

of the closure, and a spacer pivotally mounted on the extended end of said resilient contact strip, the pivoted spacer having a set position extending from the resilient contact strip and into engagement with the closure frame when the closure is closed, the spacer being automatically pivotable, when the closure is opened, to a free position wherein it does not engage the closure frame when the closure is subsequently closed.

5 2. In a portable self-contained alarm of the type including a mounting panel adapted to be secured to a closure, a circuit maker and breaker embodying a contact fixedly secured to the panel, 15 a resilient contact strip secured at one end to the panel, the other end overlying the fixed contact and extending beyond the edge of the closure, and a spacer pivotally mounted on the extended end of said resilient contact strip, the pivoted spacer having a set position extending from the resilient contact strip and into engagement with the closure frame when the closure is closed, the spacer being automatically pivotable, when the closure is opened, to a free position wherein it does 20 not engage the closure frame when the closure is subsequently closed.

25 SAMUEL SUNDEL.
